UNITED STATES PATENT OFFICE.

LOUIS P. WEBERT, OF ANNAPOLIS, MARYLAND.

METHOD OF AND APPARATUS FOR TREATING CARBONACEOUS MATERIAL.

Application filed February 16, 1920. Serial No. 359,527.

To all whom it may concern:

Be it known that I, LOUIS P. WEBERT, a citizen of the United States, residing at Annapolis, in the county of Anne Arundel and State of Maryland, have invented certain new and useful Improvements in Methods of and Apparatus for Treating Carbonaceous Material, of which the following is a specification.

10 This invention relates to a process and apparatus for the treatment of carbonaceous material such as coal, coke, coke breeze, lignite, peat, sawdust, oil shale, or any other material capable of being reduced to the pulverulent state and from which combustible gases and other products may be produced by the application of heat thereto.

I am aware that, in the past, it has been proposed to treat pulverulent carbonaceous materials such as coal and the like with heat in order to produce gases and by-products.

However, the present invention has for one of its objects the provision of a process designed to offset the disadvantages attendant upon the burning of pulverized dry coal in furnaces, wherein the disadvantages obtaining are, the high temperatures attendant upon the efficient combustion under boilers; the fine ash resulting from such combustion cannot be completely collected and therefore passes up the flue and is distributed over the neighborhood; some of the ash fuses on the brickwork and boiler tubes thereby decreasing the efficiency of the boiler, and the valuable by-products obtainable in the extraction of gas from the coal are consumed when such pulverulent coal is directly burned.

The invention also has as an object the provision of an apparatus capable of continuous treatment of pulverulent coal or other carbonaceous material for the recovery of combustible gases and attendant by-products incident to the production of such gases.

45 In the present invention carbonaceous material such as set forth in the first paragraph hereof is reduced to pulverulent form and injected under any desired pressure above atmospheric pressure at high velocity by means of a highly heated non-oxidizing gas or superheated steam, or a mixture of both non-oxidizing gas and superheated steam, into a heated retort tube in which a spiral core is fixed. The comminuted solid matter traveling at high velocity impinges against the highly heated surfaces of the tube and

the whorls of the spiral core in such manner that the minute particles of said material rapidly become of the same temperature, practically, as that of the medium in which 60 they are carried thereby resulting in practically instantaneous decomposition into their respective constituents.

The resultant solid matter and gases produced in the foregoing manner are then 65 separated by precipitating the dust and condensing those gases which normally are liquid at ordinary temperature and storing the resulting liquid and gaseous products for future use.

70 Another object of the present invention resides in the treatment of the mixture of carbonaceous material and highly heated gases passing through retorts, with a catalytic agent, for the purpose of bringing about 75 changes in the composition of the resultant gaseous products.

In the drawings:

Figure 1 is a view in front elevation of an apparatus constructed according to the 80 present invention for the purpose of carrying out the process herein set forth;

Fig. 2 is a vertical transverse section of the apparatus shown in Fig. 1 on line 2—2 thereof;

Fig. 3 is a vertical longitudinal section of the feeding means for the apparatus;

Fig. 4 is a vertical transverse section on the line 4—4 of Fig. 3;

Fig. 5 is a fragmentary view, partly in 90 side elevation and partly in section of one form of retort and spiral core;

Fig. 6 is a view similar to Fig. 5 but showing a modified form of spiral core;

Fig. 7 is a vertical section through the 95 feeding nozzle.

In detail:

One form of the apparatus for carrying the method or process into practice consists of a furnace having the vertical front and 100 rear walls 1 and 2 and the stack head 3. Within the furnace structure are located the staggered horizontal baffles 4, 5, and 6 and the vertical baffle 7, an opening 7^a being located between the baffle 7 and the wall 2. 105 The end walls of the furnace are indicated at 8 and 9.

On the platform 10 formed by a portion of the top of the furnace is a hopper 11 supported by beams 12 and 13 carrying the 110 weight of the hopper shell and the beam 14 carrying the feeding foot associated with the

hopper. The hopper is provided with an inlet pipe 15 and the bottom of the hopper is of sloping formation as shown. The feeding foot will be designated as A inasmuch as it corresponds, in construction, with a similar member used elsewhere in the apparatus and the construction of which will be hereinafter more fully described. The outlet from the foot is indicated at 16 and extends 10 downward and enters a retort tube 17 which at its opposite end is connected with a similar retort tube 18 connected, in turn, at its opposite end by a header 19 with another retort tube 18 to form a series or battery of 15 retort tubes B, the final tube 20 of which is connected by a pipe 21 with an enlarged elbow 22 which permits the product passing through the pipe 21 to have its velocity reduced and enter the hopper 23 which has an 20 outlet 24 for gases and a foot feeding device C identical with the foot feeding device A previously mentioned.

Within the hopper 23 and adjacent the outlet 24 thereof is an electrostatic dust precipitator comprising a series of plates 25 grounded on the hopper body and between which are suspended the rods 26 connected with the other pole of a suitable source of electrical energy not herein shown. From 30 the foot feeding device C the solid products enter the pipe 27 and are conveyed downwardly to a retort tube 28 of a second battery of retorts D identical with the first named battery and the outlet 29 from which 35 the mixture of gases and solid matter is led into an enlarged elbow 30 to reduce the velocity of the mixture and which enters the hopper 31 having the gas outlet 32 which has immediately adjacent thereto an electro- 40 static dust precipitator 33 identical with the one previously described. The hopper bottom enters a pit 34 and is provided with a screw conveyor 35 for removing the solid ash or coke dust.

45 Disposed within the furnace and in the path of the hot gases leaving the burner E are superheater coils F having headers G and H, the first of which is connected by a pipe 36 with a valve 37 leading to a source 50 of steam supply (not shown), a source of non-oxidizing gas supply or a source for the combination of both the steam and non-oxidizing gas supply. The superheater coils F have outlets indicated at 38 and 39 which 55 lead into the feeds to the initial retorts 17 and 28 of the retort batteries B and D respectively.

60 The front of the furnace is closed by suitable doors 40, those of the right hand half being removed for the purpose of the present disclosure and the rear of the furnace is similarly closed with identical doors likewise numbered 40 and of any suitable construction.

65 Each of the foot feeding devices A and C

is carried by a flange 41 on the hopper bottom which cooperates with a similar fitting 42 carrying the chamber 43 receiving a rotor 44 having the longitudinal grooves 45, and the shaft 46 is mounted in bearings 47 carried at opposite sides of the chamber 43. The flanged bottom 48 of said fitting 42 cooperates with the flange 49 of a tubular member 50 having the mouth 51 receiving the discharge from the rotor 45 and said tubular member accommodates a spiral conveyor 52 having a spindle 53, the ends of which are mounted in bearings 54 and one of which carries the driving pulley 55 while the other carries a gear 56 meshing with a gear 57 on the end of the shaft 46 so that by driving the pulley 55 the rotor 44 is also driven. The outlet 58 connects with the feed pipe to the retort batteries B and D as the case may be.

70 Each of the retort tubes as illustrated in Fig. 5 comprises a shell 59 flanged as at 60 and 61 to receive the heads 62 and 63 similarly flanged. Within the retort shell 59 is disposed a spindle 64 having the helix 65.

75 The construction of the retort tube shown in Fig. 6 is identical with that shown in Fig. 5, with the exception of the core 66 which consists of the spindle 67 carrying the spiral whorls 68 of a helix, the entire core is formed of some material which will act as a catalytic agent in the process, or it may be formed of a porous refractory material containing a catalytic agent.

80 The operation of the apparatus is as follows:

85 Heat is supplied from the burners E which may be fed, if desirable, from previously stored gas produced by the apparatus. The heat courses upwardly through the furnace and around the baffles 4, 5, 6, and 7 thoroughly heating the retort batteries B and D together with the superheated coils F and the hopper 23. Carbonaceous material such as coal, lignite, peat, 90 sawdust, or oil shale, is introduced into the hopper 11 and, as the rotor 44 of the foot feeding device A is driven, the pulverulent carbonaceous material is fed down into the spiral conveyor 52 and then enters the pipe 16; here it meets a jet of non-oxidizing gas such as water gas, or a jet of superheated steam or highly heated non-oxidizing gas and superheated steam traveling at high velocity and entering the feeding pipe through a nozzle and venturi indicated in general in Figure 2 of the drawings by the numeral 39' whereby an injector is formed and continuing on through the various retorts of the battery of retorts B. Due to the high velocity with which the mixed pulverulent carbonaceous material and steam or non-oxidizing gas travels minute particles thereof are carried around the highly heated whorls of the 95 spiral core contained within the retorts and 100

impinged not only against the surface of the retort but also against the surfaces of the whorls whereby they almost instantaneously become of the same temperature as their carrying medium and the destructive distillation of the particles is the result.

The products resulting from this treatment in the battery of retorts B then continue upwardly in the pipe 21 and lose considerable of their velocity in the elbow 22 from which they enter the hopper 23. Here the products are acted on by the electrostatic dust precipitator with the result that the solid particles are precipitated and the gases are collected in any suitable receiver connected with the outlet 24. Such gases are then subjected to the usual washing and condensing treatment for the recovery of by-products. The solid particles are collected in the bottom of the hopper 23 and fed by the foot feeding device C to the pipe 27 where they meet with a jet of superheated steam, non-oxidizing gas, or a combination of the two, and are carried through the lower battery retorts D constructed similar to the previously described battery but, due to being nearer to the source of heat are at a higher temperature. The products of this battery D enter the hopper 31 through the velocity reducing elbow 30 where they are acted on by the electrostatic precipitator 33 and the gases taken off through the conduit 32 while the precipitated particles of solid matter are removed by a screw conveyor 35.

While the arrangement of retort batteries herein shown is one which I may prefer to use in carrying the process into effect, it is nevertheless to be understood that the process may be equally as well performed in successive batteries of retorts arranged side by side in separate furnaces, each battery of retorts being heated and kept at any desired temperature. It is also to be understood that the pulverulent carbonaceous material may be made to pass through each battery of retorts in a continuous stream travelling at high velocity, or the stream of carbonaceous material may be interrupted at intervals in order to expose the material for a greater length of time to heat at the temperature of the retort. Inasmuch as the treatment of the gases subsequent to distillation is a matter of general knowledge in the art it is deemed unnecessary to herein show the combination of the furnaces with the mechanism for treating the gases produced thereby.

One instance of the manner of using the apparatus and carrying the method or process into effect is as follows:

The first treatment consists in subjecting the pulverulent material to a temperature of from 850 to 1400° F. this being done in the presence of a non-oxidizing gas, such as

water gas, or in the presence of superheated steam, or a mixture of non-oxidizing gas and superheated steam.

After this first treatment the resulting products are carried on around the heated whorls made of refractory material containing the catalytic agent. This step is carried out at a temperature in the neighborhood of from 1800 to 2000° F. The catalytic agent used for this purpose may be made of a mixture of three parts chromium-oxide and one part iron-oxide. On this treatment the carbon in the carbonaceous material is gasified in the presence of an excess of steam, according to the following established primary reactions:

The mixture of gases consists chiefly of hydrogen, steam, carbon dioxide, and carbon monoxide. The catalytic agent is used to bring about the oxidation of the carbon monoxide to carbon dioxide in the mixture of gases in the presence of steam according to the reaction:

It is to be noted especially that the catalytic agent is used in the presence of steam and the pulverulent carbonaceous material.

It will be understood from the foregoing that the carbon monoxide is eliminated from the gaseous products resulting from destructive distillation of the carbonaceous material and that whereas, heretofore, it had been found impracticable to eliminate carbon-monoxide directly, the present invention accomplishes this result by employing an oxidizing catalytic agent in the retorts through which the carbonaceous material is blown, so as to convert the carbon-monoxide into carbon-dioxide which may be washed out, with facility, thereby obtaining substantially pure hydrogen.

I claim:

1. The method of treating comminuted carbonaceous material for destructive distillation thereof, consisting in passing such comminuted material in a carrying medium of superheated steam through a plurality of series of retorts containing spiral cores carrying a catalytic agent, each series of retorts being heated to a different temperature to effect changes in the gaseous medium surrounding such comminuted material.

2. The method of treating comminuted carbonaceous material for destructive distillation thereof, consisting in passing such comminuted material in a carrying medium of heated non-oxidizing gas through a plurality of series of retorts containing spiral cores carrying a catalytic agent, each series of retorts being heated to a different temperature to effect changes in the gaseous medium.

medium surrounding such comminuted material.

3. The method of treating comminuted carbonaceous material for destructive distillation thereof, consisting in passing such comminuted material in a carrying medium of superheated steam and non-oxidizing gas through a plurality of series of retorts containing spiral cores carrying a catalytic agent, each series of retorts being heated to a different temperature to effect changes in the gaseous medium surrounding such comminuted material.

4. In an apparatus for destructive distillation of carbonaceous material, separate retort batteries, means for heating such retort batteries to different temperatures, a spiral core within each retort of such batteries, and means for feeding the product of one battery to the next battery through the spirals of the core.

5. In an apparatus for destructive distillation of carbonaceous material, separate retort batteries, means for heating such retort batteries to different temperatures, a spiral core carrying a catalytic agent with-

in each retort of such batteries, and means for feeding the product of one battery through the spirals of the core to the next battery.

6. In an apparatus for destructive distillation of carbonaceous material, separate retort batteries, means for heating such retort batteries to different temperatures, means for feeding the product of one battery through the spirals of the core to the next battery and including mechanism for taking off the volatile products between the batteries and precipitating solid matter.

7. In an apparatus for destructive distillation of carbonaceous material, separate retort batteries, means for heating such retort batteries to different temperatures, a spiral core carrying a catalytic agent within each retort of such batteries, means for feeding the product of one battery to the next battery through the spirals of said core and including mechanism for taking off the volatile products between the batteries and electrostatically precipitating solid matter.

In testimony whereof I affix my signature.

LOUIS P. WEBERT. [L. s.]
